UNITED STATES PATENT OFFICE

2,206,300

PACKAGE TYING MACHINE

Guy A. Dunn and John Eldridge, Oakland, Calif.,
assignors, by mesne assignments, to Francis A.
Smart, Berkeley, Calif.

Application March 17, 1934, Serial No. 699,734

40 Claims. (Cl. 100—31)

This invention relates to a machine for tying wire around boxes, bundles or other packages, and its object is to produce a machine which will be capable of continuous operation from a commercial bundle of wire without transferring the bundle or coil of wire to any part of the machine other than to feed wire through suitable tensioning pulleys.

Another object of the invention is to produce a splice or tie which will lie flat against one side of the box or bundle without the necessity of bending the twisted wire against the box as is done with some machines.

A further object of the invention is to provide means whereby the machine may make a tie and eject it in the usual way even though it may happen to be tripped accidentally, and even though no bundle is then in the machine. In this event, a very small tie is produced on a projecting plate of the box-supporting table, and the ejecting apparatus pushes this tie off the plate in the same way as the tie is pushed off when it is placed around a bundle.

Another object of the invention is to provide means whereby the bundle or boxes may be pushed against a side guard just prior to the time the tie is tied around to insure holding them in the proper place while the tie is being made, but this mechanism is only intended for holding the package and not intended to compress it.

Another object of the invention is to provide means whereby the tie end when cut off will be carried around by the shuttle to the starting position there to be secured anew at a moment just prior to the time for the next turn of the wire around the next box, means being provided to move the tie end away from the bundle first and to thereafter cause it to project toward the bundle to insure its proper positioning in the apparatus.

Another object of the invention is to provide means whereby the box or bundle will be automatically carried out of the machine whenever the center of gravity of the box or bundle is far enough over the feed rollers.

Another object of the invention is to provide a machine of the character described with a ring capable of rotating first in one direction and then in the other to first carry the tie around the box and to then bring the cut-off tie end back to a position adjacent the box or bundle where it can be later secured for the production of another tie when the clutch has been tripped.

Other objects of the invention will appear as the description proceeds.

An embodiment of the invention is shown in the accompanying drawings in which the same reference numeral is applied to the same portion throughout, but we are aware that there may be modifications thereof.

Figure 1 is a view in elevation of the complete machine looking in the direction of feed; Figure 1^a is a detail of the shuttle control track taken on the line 1^a—1^a Figure 1.

Figure 2 is a view in elevation of the complete machine looking in the opposite direction from Figure 1.

Figure 3 is a side elevation of the machine 15 looking from the left of Figure 1.

Figure 4 is a side elevation of the complete machine looking from the right, Figure 1.

Figure 5 is a sectional view of the interior operating mechanism of the machine looking in the same direction as Figure 3 taken on the line 5—5 of Figure 6.

Figure 6 is a view of the interior operating mechanism of the machine partly in section, looking in the same direction as Figure 4, the shuttle and support therefor being omitted in both of the latter figures.

Figure 7 is an enlarged detail view, in section, of the device for cutting off the over-fed tie end and for holding the wire ends when wrapped around the package.

Figure 8 is a view looking from the right of Figure 7, showing the end of the package feed table and showing the relation of the wire grippers, twisting mechanism and ejectors thereto; Figure 8^a is a plan partly in section of a modified form of twister.

Figure 9 is a plan view of the ejectors and twister slide portions of the package supporting table being broken away for purposes of illustration showing the twister gear advanced over the ends of the wire; Figure 9^a is a vertical sectional view of a portion of the twister mechanism shown in Figure 8^a taken on the line 9^a—9^a, Figure 8^a.

Figure 10 is a side elevation of the main drive spur gear showing the cam for lifting the discharge roller.

Figure 11 is a side elevation of the opposite side of the same gear showing the cam for operating the slide to push the package and tie off the feed table.

Figure 12 is a side elevation of the secondary drive gear showing the cam for the operation of the twister slide.

Figure 13 is a side elevation of the opposite side of the gear shown in Figure 12, showing the cam for operating the twister rack.

Figure 14 is an edge view of the cam for operating the shuttle finger control.

Figure 15 is an edge view of the cam for operating the package holding means during the time the tie is being made.

Figure 16 is a side elevation of both the cams shown in Figures 14 and 15.

Figure 17 is a side elevation of the cam for operating the D wire grip.

Figure 18 is a side elevation of the cam for operating the B wire grip.

Figure 19 is a side elevation of the cam for operating the C wire grip.

Figure 20 is a side elevation of the cam for operating the A wire grip, the degree lines on Figures 10 to 13 and Figures 14 to 20 indicating the beginning and ending of the changes in curve of the cam surfaces in each instance.

Figure 21 is a vertical section on the line 21—21, Figure 22 of the starting clutch.

Figure 22 is a sectional view substantially on the line 22—22 of Figure 21, of the starting clutch mechanism.

Figure 23 is a side elevation of a portion of the shuttle and the shuttle ring.

Figure 24 is a view of the shuttle, a portion of the shuttle carrying ring and a portion of the shuttle operating cam.

Figure 25 is a detail view of the means for operating the package holding means when the package is being tied.

Figure 26 is a view of tie made when no package is in the machine.

Figure 26a is a view of the splice looking in the direction of the arrow of Figure 26.

Figure 27 is a vertical sectional view looking in the same direction as Figure 1, of the shuttle ring and other parts of the machine taken substantially on the line 27—27 of Figure 3 showing the shuttle ring at the end of movement, after carrying the main body of the wire around the package.

Figure 28 is a plan view of the parts secured to the under side of the box supporting the table with the table showing only at the margin of the figure.

Figure 29 is a vertical section on the line 29—29 of Figure 6 looking in the direction of the arrow.

Figure 30 is a vertical sectional view of the higher portion of the base, showing the cam shaft and gears in the side of the same upon a larger scale than Figure 6, and in practically the same sectional plane.

Figure 31 is a vertical sectional view of the parts found in Figure 30, the plane of section being shown at 31—31, Figure 30 looking in the direction of the arrows.

The machine has a rectangular box-like base 1 higher at one end than at the other, as indicated at 2, and inside of which base the operating gears, shafts and cams are installed. Extending above the lower portion of the top of the box or base there is a standard 3 for the support of the shuttle ring 4. Secured to the top of the raised portion 2 are two standards 5 and 6 which are bolted to said top for the support of a plate 7, which affords an abutment against which boxes or bundles may be placed by the workmen.

In order to make it convenient to move the machine from place to place, the base has two rollers 8 and 9 vertically under the standard 3, and at the front it has a bracket 10 which rests

upon a shank 11 which has a transverse shaft 12 to receive 2 castor wheels 13 and 14. The vertical shaft 15 is connected to and extends from the support 11 through the bracket 10 to permit the castor wheels to rotate as may be required when the machine is to be moved. This shaft has a collar 16 to prevent dislodging the shaft from the bracket 10, should it be desired to raise the machine and place it upon cross-bars above the floor level. The shuttle ring is indicated at 4 and it is mounted on five rollers 19 to 23 which are in turn revolvable on short shafts carried by brackets 24, 25, 26, 28 and 29 extending inwardly from the fixed supporting ring 3. This oscillating shuttle ring is provided with gear-teeth 18 on its periphery for turning it from its initial position through its cycle of movement to carry the wire holding grippers 196, as well as four grooved pulleys 101 to 104 inclusive over which the wire passes to the tension pulleys 35, 36. The tension pulleys consist of a plurality of grooved pulleys lying side by side and revolvable on the shafts 37, 38 so that the series of pulleys 38 lie immediately under the series of pulleys 35. (See Figure 1.)

The shaft 37 is carried by a bracket 39 which bracket also has a rod 40 pivotally supported thereby at 41. This rod is provided with a rubber bumper 42 near its upper end and with a rubber bumper 43 at its lower end. Slidable on this rod is a bearing 44 which has two flat striking surfaces 45, 46, which will come in contact with the rubber bumpers when necessary.

A lever 47 is pivotally connected to the slide bearing 44, and it is also pivotally connected at 48 to the top of a cylindrical housing 49 secured on the side of the main frame. This cylindrical housing is closed on the end by means of a plate 50. At the top of the machine there is a bracket 51 which carries a guide pulley 52, and this pulley has a plate 53 with a hole 53' in it to direct the wire on said pulley. (See Figure 27.)

Immediately below the pulley 52 there are five straightening rolls 54 to 58 inclusive between which the wire must pass before it can pass under one of the tension pulleys 36. The wire then passes over as many of the tension pulleys as may be deemed necessary, passing from one of the upper pulleys 35 to the supporting pulleys on the side of the shuttle ring 4, and then passing completely around the shuttle pulley 103 to the shuttle guide plate 194 and extending a short distance beyond as shown at 137. (See Figure 1.)

Extending through the base of the machine are two main shafts 60, 61, while there are three other shafts 62, 63, 64, which also extend through the sides of the base.

The machine is driven by the worm 65 which engages the worm wheel 66, said worm being fixed to the shaft 67' and revolvable therewith. This shaft 67' extends into two bearings 68, 68' and carries said worm 65 within a small raised housing 69 on the top of the housing (see Figures 3, 21 and 22).

The shaft 67' has a pulley 70, around which a belt 71 passes from the pulley 72 on the shaft of the motor 73, the frame standard 3 having a bracket 74 to provide a place of operation for the motor on the top of the ring frame.

Inasmuch as the shaft 67', carrying the worm 65, drives the entire machine, there is a plate 75 which encloses a suitable bearing for the end of that shaft. Since the machine runs freely at times and pulls at other times, there is a brake

ring 76 secured around a boss 77 on the shaft 60, and a bolt 78 is used to hold this brake ring in a fixed position, another bolt 79 being used to adjust the tension of the brake so that the machine will run smoothly at all times. (See Figures 1, 2 and 3.)

The shaft 60 rotates in bearings 80, 81 and 82, and has a belt wheel 83 on the end opposite from the worm wheel carrying a crank pin 84. A belt 85 passes around the wheel 83 and over a pulley 86 for the operation of the bundle feeding apparatus later to be described.

The machine is operated from the main wheel 83 and crank pin 84 by a rack pitman 87. This pitman 87 is connected to the crank pin 84 by the cap bearing 88, and it is slideable through a bearing 89 which is loosely mounted on the shaft 90. The object of this bearing is to hold the rack engaged with the gear 91. (See Figures 1, 2 and 4.)

The shaft 90 is mounted in two bearings 91' and 92 on the back of the machine (see Figure 2) and it carries a beveled gear 93 which is in mesh with a beveled gear 94 on a stub shaft 95, the latter shaft extending perpendicular to the plane of rotation of the ring 4. This stub shaft has a spur gear 97 thereon in mesh with a smaller spur gear 98 on the shaft 99, and said shaft also carries a spur gear 100 which has its teeth in mesh with the teeth 18 of the ring 4.

The result of the construction just described is that each time the shaft 60 is operated, the rack 87 will operate the gear trains connected therewith to turn the shuttle ring once around 35 and back to its position of rest, that position being indicated in Figure 1. The shuttle ring carries four grooved wheels 101, 102, 103, 104. The wire passes from one of the upper take-up pulleys 35 over the groove pulleys 101, 102 and 103 when the machine is at rest, as shown in Figure 40 1, and under the groove wheel 104 when the ring 4 is at the end of its first movement, as shown in Figure 27.

Extending around the outside of the main frame 3 are two circular flanges 107, 108, which 45 with a movable cam 109 pivoted at 110, and also provided with two flanges 111, 112 forms the means for moving the wire holding shuttle assembly 105 in the proper position to pass under the corners of the packages in a manner presently to be explained. (See Figures 1, 1^a, 4, 23, 24 and 27.) The cam 109 is operated by a link 113 and lever 114, its position of rest being shown in Figure 1. This cam has its flanges 50 overlapping the flanges of the fixed frame as shown in Figure 1^a at 115, 116, 117, 118 to afford a smooth track for the shuttle assembly roller 119.

The raised portion 2 of the base 1 is covered 60 by a flat table or box support 2' which is secured thereto and which forms the support for the several parts of the wire holding and twisting mechanism shown in Figures 5, 7, 8 and 9.

Extending forwardly from the top of the table 65 2' are two horns 122, 123, under which the wire 121 is carried by the shuttle ring, which horns are thick enough to allow the necessary space for the operation of the twister gear 124. (See Figures 8 and 9.)

In order to prevent dirt from accumulating in 70 the teeth of said gear 124 and to prevent inadvertently made ties from falling down in the machine where they might interfere with the operation of the machine, there is a plate 125 which is secured over the horns and which ex-

tends over the discharge plate 126. (Note Figure 7.)

Extending transversely under the table 2' there are two shafts 127, 128 one of which carries an arm 129 and the other of which carries an arm 130. (See Figures 6, 7, 8, 9 and 31.) Mounted on the shaft 127 is a tube 131 carrying an arm 132, while the shaft 128 has a tube 133 with an arm 134. The arm 132 has an L-shaped plate 135 thereon which has a spring 136 thereon to insure pushing the cut-off wire end 137 down as shown in Figure 8. Just outside the horns 122, 123 there are the pusher bars 138, 139, their object being to push the box and tie, or the tie alone, if a tie is made without a box or package in the machine, ahead until the tie passes the end of the plate 125.

The order of operation of the levers 129, 130, 132 and 134, is indicated in Figure 8, by the letters A, B, C, D. In the first place when the wire 20 shuttle presents the wire following the "at rest position," the lever 130 will come up against the wire to hold the wire end 137 in place. The shuttle will then begin to wind the wire around the package, whereupon the arm 132 will rise 25 and bear on the wire under the horn 122.

The shuttle then carries the wire around the package and it will contact with the end of the arm 130 and snap into a position closely, alongside the other end of the wire, whereupon the 30 arm 134 comes up and bears on the wire under the horn 123 and said arm is also provided with a cutter 134' (see Figure 7) to cut off a small piece of the tie end which is overfed to be sure of placing it for proper operation of the first 35 lever 130. Almost at the time the arm 134 is rising the arm 129 begins to rise and as the wire end 137 has been fed under the end of the arm 132, said arm 129 cuts off the wire against the underside of arm 132 where it is marked B. The arm 129 is also provided with a pin 129' to prevent the wire from slipping off during the time it is placing the wire in position to tie. The spring 136 is for the purpose of disengaging the 40 cut-off wire end 137 from the edge of the fixed cutter, and forcing it downward, as shown in Figure 8. It will be seen that the pin 129' passes into a hole in the horn 122 when the arm 129 is up against the wire.

The gear 124 is slotted to receive the two wires 50 and it has two hollow trunnions 140, 141 which are journaled in the two slideable bars 142, 143, and said gear is rotated by the rack bar 144 which is slideable in the two bars 142, 143.

From an examination of Figure 8 it will be apparent that eight separate complete movements must be provided for, as follows: (1 to 4) the arms must be pushed up against the wire, in their proper order, (5) the slides 142, 143 must be advanced with the gear 124, (6) the rack 144 must be advanced to rotate the gear 124 and (7 and 8) the two bars 138, 139 must be advanced to push the tie over onto the table 126. The movement of the bars 138, 139 is accomplished by means of two segment gears 145, 146, mounted 65 on a shaft 147, the teeth of said gears engaging the teeth in the under-side of the bars 138, 139. The two segment gears are operated by the two turn-buckle links 148, 149 pivotally connected to two levers 150, 150' which levers are keyed to as shown on Figure 5 and supported by a shaft 62. The lever 150' has a roller 153 which is directed by the cam groove 229' on one side of the gear 154 so the two ejector bars 138, 139 are operated in unison. When the package 70 75

has been completely tied the bars 138, 139 which are slideable under the table top 125 are advanced by the movement of the segment gears 145, 146 to push the package ahead far enough 5 to release the tie from the twisting mechanism, the ends of said bars engaging the tie on opposite sides of the twisting gear 124, and outside of the horns 122, 123.

The gear 154 has cams 229, 229' on its opposite sides, the relation of the curves of said cams being indicated in degrees on Figures 10 and 11, and said gear is in mesh with another gear 155 having the same number of teeth, and which is mounted upon shaft 61. The gear 155 has the 15 cam grooves 155', 155'' on its opposite sides and the relation of the curves of said cams is indicated in degrees on Figures 12 and 13.

The shaft 64 is substantially in the same horizontal plane as the shafts 60, and 61 and just out 20 of engagement with the gear 155 carries six bell-crank 158 to 163 inclusive for the operation of the other six movements of the tying apparatus located at the front of the table 2'. These bell-crank are of the two sizes shown in Figure 6, the 25 two inner ones 160, 161 operating the slide rack bar 144 and the two bars 142, 143 respectively.

The two bars 142, 143 are connected at one end by the plate 164 (see Figs. 6 and 30) which has a depending bearing for a pivot pin 165 supporting one end of a link 166, the pin 167 supporting the other end of the link and connecting it to the bell-crank 161. (See Figures 6 and 28.)

Each of the said bell-crank 158 to 163 has a roller bearing on one side thereof as indicated at 30 170 on the bell-crank 163 to enter the cam grooves 35 of the gear 155 and the cams 156 and 157.

For the operation of the wire gripper 132 the 40 tube 131 has a depending arm 171, the shaft 127 and arm 172, the shaft 128 a depending arm 173 and the tube 133 a depending arm 174, said arms being connected by four short links 175 to 178 to 45 four other upwardly projecting arms 179 to 182 journaled on the shaft 63. All four of the arms just mentioned are in turn connected pivotally, by turn buckle links 183 to 186 with the four bell-crank 158, 159, 162 and 163, one for each 50 crank. (See Figures 6, 7, 27, 28, 29, 30 and 31.)

The shuttle consists of a block 190 which is secured to a projecting tube forming a hub on 55 one side of the gear 191 by a bolt 190'. Secured to the arm 199 and extending through the hub of the gear 191 and said block 190 is a stud 193 on which the grooved wheel 103 is revolvable. (See Figures 23 and 24.) Just in front of this wheel 103 and secured to the blocks 190 is a grooved 60 plate 194 which forms a sort of finger to hold and direct the wire end as desired. This wheel has the wire passed around it, as indicated in Figures 1 and 27 for the purpose of so curving the wire that it will be normally convex toward 65 the package when cut, thereby causing it to be perfectly flat on the package. On the upper side of the block there is a disk-like plate 195 on which there is a knurled wheel 196, held from rotation in one direction by the pawl 197 on which a spring 198 bears. (See Figure 24.)

The grooved guide plate 194 and the knurled 70 wheel 196 with its pawl 197 and spring 198 form a unidirectional feed means for the wire. The knurled wheel 196 is permitted, by the pawl 197, to rotate in the direction of the feed of the wire when passing a tie around the bundle, but is locked by the pawl 197 from rotating in the opposite direction when the tie has been cut and thus prevents the wire end 137 from being withdrawn 75

from the shuttle by the tensioning wheels 35 and 36.

The entire shuttle mechanism is carried by a short arm 199 bolted on the side of the shuttle gear-ring 4 and the shuttle itself is operated to move the wire toward and away from the package to give the necessary clearance at the corner of the package adjacent the bottom of the plate 7.

This movement is effected as follows: The 10 block 190 and gear 191 are rigidly connected, and the latter gear is in mesh with a gear 200 on a shaft 201 which extends through the ring 4. This shaft has an arm 202 rigidly secured thereto, which shaft has a roller 119 on a short pin 204. 15 (See Figures 23 and 24.)

The roller 119 travels in a circular groove formed by the two flanges 107, 108 on the main frame 3. This groove has the movable section 109, previously referred to, which at the time the 20 wire end is to be presented to the gripper, raises the shuttle and wire end toward the A gripper, but since the shuttle must pass the corner again at the end of its first movement, means are provided including the link 113, arm 114, keyed on 25 the shaft 207 and an arm 208, keyed on the same shaft to bring the bottom of the movable cam track 109 down into engagement with the lower ends of the flanges 107 and 108, at the proper time for it to hold the shuttle away from the 30 package at the end of its half cycle operation. This movement is effected by the cam 208' which has a peripheral groove to receive a roller 208a on the lower end of the arm 208. (See Figures 1, 5, 6 and 15.)

In order to push the package against the plate 1 to prevent the wire from turning the package over when the wire is passed around the same there is a movable plate 210 on a horizontal shaft 211 which has rack teeth on its under side 40 in mesh with the teeth of a pinion 212 which pinion is carried by a shaft 213 which has the hand crank 214, said crank carrying a pin 215 (see Figure 3) for engaging holes in a disk 216 to hold the pusher in any desired adjustment. (See Figures 1, 2, 3 and 25.)

The shaft 213 and disk 216 are both supported by a tubular slide 217 which has teeth on its lower side in mesh with a gear 218 on a shaft 219, and this shaft also carries a gear 218' which 50 is in mesh with a vertically slideable rack 220, said rack being held engaged with said gear by the bearing 221. At its lower end rack 220 is connected to a lever 222 on a short shaft 223, which shaft also has a depending arm 224 thereon inside the base which arm has a roller 225 thereon in mesh with the groove of the cam 226. The result of the above construction is that the movable plate 210 can be adjusted to any desired position, but with each tie made the movable plate is moved toward the fixed plate 1 a small amount to hold the package securely while the wire is being carried around the bundle.

Loosely mounted on the shaft 62 is a lever 227 which has a roller 228 bearing on the cam 65 229 on the gear 154, the object of which is to raise the plate 230 through the connecting rod 231. It will be seen that the plate 230 is pivotally mounted on the shaft 86', and it has three gears 232, 233, 234 thereon, the latter in mesh with a 70 gear 235 on shaft 86'. (See Figures 5, 6 and 10.) The shaft carrying the gear 232 has a series of serrated disks 236 thereon which project through slots 237 of the floor 126. The object is to push the disk 236 up against the bottom of the pack- 75

age to eject it from the machine when the tie is completed, or whenever the center of gravity of the package is near enough over the disk to make it effective. (See Figures 2 and 6.)

It will be seen that the shaft 60' is supported in two journal boxes 240, 241, on the lower portion of the main frame 3. The shaft is driven by the belt 86 previously mentioned, and the belt is tightened by the pulley 85.

The machine is started into operation by the attendant stepping on a lever 246 on a shaft 243, journaled in two boxes 244, 245 on the lower flange of the base 1. (See Figures 2, 3, 21 and 22.) The shaft 243 has a lever 248' thereon which has a short link 247 connecting it to the lever 248 on the shaft 249. (See Figures 2, 21 and 22.) The shaft 249 is journaled in two bearings 250, 250' formed in the lower part of the housing 46. (See Figure 22.) This shaft 249 carries a block 251 with its upper end curved to fit the hub 252, said hub being secured on the shaft 60. The hub also carries a pawl block 253 which can be lifted up to the position shown in Figure 22 whenever the lever 248 is released, 5 pulling the lever up and causing the block 253 to be disengaged from the notches 255 inside the hub of the gear 68 on exactly one turn of the shaft 60 which completes one entire cycle of all of the operations of the machine.

10 The operation of the machine is as follows:

The wire is placed on a suitable support in such a way as to prevent the bundle of wire from tangling, and with the end leading through the plate 63 to the roll 52, and then through the straightening rolls 54 to 58, the two rolls 55, 57 on the slide 57' being set at the proper position with the adjusting screw 56' to properly hold and straighten the wire.

40 The wire is then passed under and over the grooved pulleys 35, 36 several times (see Figure 3), and then over the grooved wheels 101, 102 and reversely around the grooved wheel 103, the object being to curve the wire so it will lie close to the package. The wire end is then projected 45 6 or 8 inches from the end of the plate 194. As the machine stands at rest the shuttle is raised with two wire ends about an inch below the horn 123, Figure 8, and the first movement of the machine causes the A gripper to push the wire up against the horn 123 and to clamp the wire thereto.

45 The workman then places a package to be tied on the table 2' alongside the plate 7 at the point where it is desired to encircle it with the tie and 50 steps on the pedal 248.

55 The dropping of the pawl 253 causes the gear 68 to start the machine, the first operation being to cause the A grip to engage the wire. The shuttle ring being driven by the crank pin 84 and rack 87 starts slowly, stops and starts slowly at the end of its half cycle, and then stops slowly when its movement is being completed thereby making for most efficient running of the machine. The operations just described are carried out in the manner suggested by reason of the position and action of the driving crank-pin 84 with respect to the gear 91.

60 At the same time the clamp A is operating, the movable plate 210 pushes the package over tightly against the plate 7 to hold it in place while the wire is being carried around the package. As seen the shuttle clears the corner of the package in the first part of its movement which is away from the center of the ring because 75 of the shape of the movable track then engaged

by the roller 118, the B clamp comes up and engages the wire. No other operation than the turning of the ring carrying the shuttle takes place now until the ring has traveled a considerable part of the distance around when the 5 movable track 169 moves down into alignment with the rest of the track preparatory to the entrance thereto of the roller 119 at the end of the half cycle movement of the ring.

10 As the ring brings the shuttle under the package the C gripper comes up and cuts off whatever end there may be of the wire projecting more than is necessary, this extra piece, about one-half inch long being provided to insure the A gripper catching and securely holding the wire. 15 The next step is for the D gripper to come up against the wire and cuts off the length around the package against the B gripper. The horn 120' holds the two wires snugly together. The spring 138 has in the meantime, been compressed and as soon as the wire is cut the wire end is thrown down to the position shown in Figure 8.

20 The shuttle ring is now at the end of its half cycle movement, and has no further function than to return to its initial starting position, the tightening wheels in the meantime keeping the desired tension on the wire.

25 During the time the shuttle ring is returning the slide carrying the gear 124 is advanced to 30 bring it over the two wire ends in the position shown in Figure 9, and when so advanced the gear is rotated two turns to produce the tie. As soon as the tie is completed the slide and gear 124 are both retracted, and the two pushers 138, 35 139 are advanced to push the tie off the horns 122, 123 and to carry the package ahead about four inches.

30 During the time the shuttle is turning over and back the disk 238 is being rotated, but not 40 until the tie is completed is the disk raised to aid in pulling the package out of the machine. When placing two ties around a 26 pound dried fruit box, the disks 238 do not catch the box on the first tie, but when the second tie is made 45 it slides the box clear of the machine at once.

45 When the shaft 60 has made just one turn the pawl 253 is pushed up into its recess out of engagement with the notches of the hub of the wheel 68, and the machine stops. In actual 50 practice the men become so skillful in feeding boxes into the machine that they will place a weight on the lever 248 and allow the machine to run steadily pushing a box into place after each time. If a tie is made without a package 55 in place the tie is completed and ejected from the machine as shown in Figure 26 with no damage to the machine.

55 It will be understood by those skilled in the art that this machine is capable of tying boxes, 60 bundles or packages of any kind or size, so long as they are small enough to pass through the space between the wheels for supporting the revolvable ring. The term "packages" is used herein to cover any kind of a box or bundle tied 65 by the machine.

65 In the form of the twister shown in Figures 8^a and 9^a, the twister gear is shown at 258a, and 70 it has hollow trunnions on both sides exactly the same as shown in Figures 8 and 9, but it is supported by two fixed bars 251', 252' cut away at the bearing 90 degrees apart, as shown in Figure 9^a, the wire being laid in the gear by the shuttle when said gear is at rest, whereupon the grip- 75

pers operate in the same manner as in the other figures.

When the wire is placed in position the gear

- 5 is turned one and three quarter turns or two and three quarter turns by the gear 253" which is driven by the rack 253', so the gear then stands with its wire receiving slot horizontal (see the dotted lines Figure 9a), and ready for the pushers to push the wire tie and package off
- 10 just as in the other case. The rack 253' is operated by precisely the same means as the rack 144 except for the distance of movement. In order to insure holding the twister gear securely, a pair of plates 255', 256 bear on the twister gear
- 15 trunnions 257, 258, plates extending from the main frame the same as the plate 126. The extra gear 253" is required to operate the gear 250a because in one position the slot therein must be kept clear for the reception of the wire.
- 20 It will be noted that both portions of the wire between the grippers have had the tension released by the action of the grippers before the twisting takes place whereby that portion of the wire being spliced has to withstand only the strain of forming the splice.

By the term "flat splice" used in this specification is meant that kind of a splice of the wire ends in which the completely twisted ends lie substantially parallel to one side of the package

- 25 which has been tied, and which splice requires no bending of any kind to bring the twisted ends parallel to one side of the bundle or box after the splice has been completed.

We claim:

- 25 1. In a package tying machine, a reversely revoluble shuttle ring, means to secure a wire end thereto, means to turn the ring to encircle a package with wire and to restore the wire to its initial position, means to cut off a length of
- 40 wire, and means to twist the wire into a splice between its ends.

- 2. In a package tying machine, a reversely revoluble shuttle ring, means to secure a wire end thereto, means to turn the ring to encircle a package and to restore the ring and wire end to their initial positions, means to cut off the wire of the proper length so the ends will lie alongside of each other for a short distance, and means to twist the wire into a splice along one
- 45 side of the package.

- 3. In a package tying machine, a reversely revoluble shuttle ring, means to secure a wire end thereto, means to turn the ring to encircle a package with a wire tie and to restore the ring and wire to their initial positions, means to cut off the wire, means to grip and hold both wire ends so they will extend in opposite directions alongside of each other for a short distance, and means to twist the wire into a splice
- 55 60 to lie flat along one side of the package.

- 4. In a package tying machine, a reversely revoluble shuttle ring, means to secure a wire end thereto, means to turn the ring to encircle a package and to restore the ring with a projecting wire end to the initial position of the ring, means to cut off the wire of the proper length so the ends will lie alongside of each other for a short distance, grippers to hold the two wire ends in a fixed position, and means to
- 65 70 twist the wire into a splice to lie flat alongside the package.

- 5. In a package tying machine, a reversely revoluble ring, a shuttle carried by the ring, means to secure a wire end thereto, means to
- 75 turn the ring to encircle a package and to restore

the ring with a projecting wire end to the initial position of the ring, means to cut off the wire of the proper length so that the ends will lie alongside of each other for a short distance, grippers to hold the wire ends together, means to twist the wire into a splice to lie flat alongside the package, and means to move the shuttle to present the wire end to one of the grippers.

6. In a package tying machine, a reversely revoluble ring, means thereon to carry a wire around a package, a wire gripper, means to move the wire end toward the package to present it to the gripper, means to cut off the wire when passed around the package, and means to twist the wire into a splice so it will lie flat alongside the package.

7. In a package tying machine, a reversely revoluble shuttle ring, a shuttle for holding a wire secured to said ring, a set of wire grippers, means to move the shuttle to present the wire end to one of said grippers before the wire is carried around the package, means to hold the package when the wire is being carried around the same, and means to twist the wire into a splice to lie alongside the package.

8. A package tying machine, comprising a reversely revoluble shuttle ring, a wire holding shuttle carried thereby, grippers to hold the wire when it is being carried around the package, means to twist the wire into a splice, and a slide for pushing the spliced wire and package secured thereby off the splice forming mechanism.

9. A package tying machine, comprising means to carry a wire around and to splice it so the splice will lie flat alongside the package, a pair of slides for engaging the wire at opposite ends of the splice to move the spliced wire and package until the wire is free from the splicing mechanism, and a carrier to eject the package from the machine.

10. A package tying machine, comprising a reversely revoluble shuttle ring, means thereon to secure a wire thereto, a package supporting table having an overhanging plate under which the wire is carried, means under said plate to secure the wire ends in a fixed position and to cut off the wire of the proper length, and means to twist the wire into a flat splice.

11. A package tying machine comprising a supporting frame, a reversely revoluble shuttle ring, means to secure a wire thereto, a package support, grippers to hold the wire ends together below said support, means to twist the wire ends together, and means to push the wire and package off the tying mechanism.

12. In a package tying machine, a supporting frame, a reversely revoluble shuttle ring, means to secure a wire thereto, means to rotate the ring to carry the wire around the package and restore it to its initial position, a plurality of grippers to hold the wire ends, means to twist the wire into a splice along one side of the package, and means to move the tie and package off the tying mechanism.

13. In a package tying machine, a supporting frame, a reversely revoluble shuttle ring, a shuttle on said ring, means to supply said shuttle with wire, means to support a package adjacent said ring, means to rotate said ring around the package and back to its initial position to place a wire around the package, means to cut off the wire so the ends will extend along one side of the package, and means to twist the wire into a flat splice.

14. In a package tying machine, a supporting

frame, a reversely revoluble ring, means to secure a wire thereto, means to rotate the ring around the package once and to restore it to the initial position, means to advance the wire end toward the package, grippers to hold the wire ends, means to twist the wire into a flat splice with the twisted portion not under tension when so held, and means to remove the package and tie from the twisting mechanism.

15. In a package tying machine, a supporting frame, a reversely revoluble shuttle ring, means to secure a wire thereto, means to rotate the ring around the package and back to its initial position, grippers to hold the wire ends together without a strain on the parts of the wire between the grippers, and means to twist the wire into a flat splice when so held.

16. In a package tying machine, a reversely revoluble shuttle ring, means to secure a wire thereto, means to rotate the ring around the package to carry the wire around the package and to return the ring to its initial position, means to cut the wire of the proper length, a plurality of grippers to hold the wire ends together without tension on that portion of the wire between the grippers, and means to twist the wire into a flat splice along one side of the package.

17. In a package tying machine, a reversely revoluble shuttle ring, means to secure a wire thereto, means to rotate the ring around the package once and back to its initial position, a plurality of grippers to hold the wire ends alongside each other without tension, means to twist the wire into a flat splice, means to push the package when tied away from the twisting mechanism, and means to remove the package from the machine.

18. In a package tying machine, means to pass a tie around a package, means to secure the tie thereto, means to cut the wire of the proper length, and a spring to disengage the wire from the cutter.

19. In a package tying machine, means to pass a wire tie around a package, wire grippers having means to cut off a tie, means to secure the tie to the package, and means to move the end of the wire into the path of one of the grippers after the first-mentioned means is restored to its initial position.

20. In a package tying machine, a reversely revoluble shuttle ring, a wire holding shuttle thereon, a package holding table, means to rotate the ring around the package once and to restore it to its original position, grippers having means to cut off a tie, means to secure the wire to the package, and means to move the wire end held by the shuttle into the path of one of the grippers after the ring has come to rest.

21. In a package tying machine, a reversely revoluble shuttle ring, having a wire holding shuttle adapted to carry a wire tie around a box in one direction under tension, and have the ends lie parallel with the box, means to release the tension on a portion of the ends lying parallel with each other, and means to twist said ends together under said released tension.

22. In a package tying machine, a reversely revoluble shuttle ring, a wire holding shuttle thereon, means to hold a package, means to revolve said ring in one direction to carry a wire around said package under tension, means to lap two ends of said wire, means to hold the tension on the package, means to release the tension on a portion of the lapped ends, means to twist said portion of said lapped ends to form

a tie, and means to return said shuttle ring to its original position.

23. In a package tying machine, a shuttle ring having a wire holding shuttle thereon, means to revolve said ring in one direction to carry a wire under tension around a package, means to lap the ends of said wire, means to release the tension on the lapped portion of said wire ends, means to hold the tension on the wire encircling said package, and means to twist said lapped ends together during the released tension thereon.

24. A package tying machine comprising a frame, a shuttle ring mounted to revolve in said frame, a wire holding shuttle on said ring, the end of said wire adapted to be held by said shuttle and carried around a package under tension inside said ring, means to cut off the wire leaving two lapped ends, means to hold said ends to release the tension on the lapped portion thereof, and means to twist said ends together to form a tie.

25. A package tying machine comprising means to wrap a wire around a package under tension, means to cut off the wire leaving two lapped ends, spaced means for holding said ends whereby the tension on that portion of the ends lying between said holding means is released, and means to twist said ends together.

26. An automatic wire tying machine comprising a first gripper, a twister, a second gripper and a third gripper, means for wrapping a wire around a bundle, and means actuating the grippers and twister whereby the ends of the wire are held in the twister by the first and second grippers, and the wire is cut by the shearing action of the third and second grippers.

27. In a tying machine, a reversely revoluble shuttle ring, having a wire holding shuttle adapted to carry a wire tie around a box in one direction under tension and have the ends lie adjacent along one side of the box, means to release the tension on a portion of the adjacent tie ends, and means to twist into a splice said tension released portion of the tie ends.

28. In a tying machine, a reversely revoluble ring, a shuttle carried by the ring, means to turn the ring to encircle a package with a tie and to restore the ring to its initial position, means to cut off the tie of the proper length so that the ends will overlap, grippers to hold the tie ends, means to twist the tie adjacent its gripped ends into a splice, and means to move the shuttle to present the tie end to one of the grippers.

29. In a tying machine, a reversely revoluble shuttle ring, a wire feed means secured thereto, means to turn the ring to encircle a package with a wire tie and to restore the ring to its initial position, means to cut-off the wire of the proper length so the ends will overlap each other for a short distance, grippers to hold the two wire ends in a fixed position, and means to twist the wire into a splice to lie flat alongside the package.

30. In a tying machine, a reversely revoluble shuttle ring, a uni-directional wire feed means secured thereto, means to turn the ring to encircle a package with a wire tie and to restore the ring to its initial position, means to cut-off the wire, means to grip and hold both wire ends so they will extend in opposite directions adjacent each other for a short distance, and means to twist the wire into a splice to lie flat along one side of the package.

31. In a tying machine, a reversely revoluble shuttle ring, a uni-directional wire feed means

secured thereto, means to turn the ring with said uni-directional wire feed means to encircle a package with wire and to restore the ring and wire feed means to their initial positions, means to cut off the wire of the proper length, and means to twist the wire into a splice along one side of the package.

32. In a tying machine, a reversely revoluble shuttle ring, a uni-directional wire feed means secured thereto, means to turn the ring together with said wire feed means to encircle a package with wire and to restore the wire feed means to its initial position, means to cut off a length of wire, and means to twist the wire into a splice between its ends.

33. In a wire tying machine having a supporting frame, a shuttle ring rotatably mounted thereon, means for reversely rotating said ring, a shuttle pivotally mounted upon said ring, a cam means pivotally mounted upon said frame and having means for actuating said cam means during predetermined portions of the tying cycle, a shuttle oscillating means mounted upon said shuttle ring operatively related with said shuttle and said cam means during a portion of the tying cycle for oscillating said shuttle, means mounted upon said frame and in operative relation with said cam means and said shuttle oscillating means for controlling the movement of said shuttle oscillating means and thereby said shuttle during a portion of the tying cycle.

34. A shuttle oscillating means for a tying machine comprising a fixed cam mounted upon the frame of said machine, an oscillating cam pivotally mounted upon said frame and operatively associated with said fixed cam, means for oscillating said cam at predetermined portions of the tying cycle, shuttle oscillating means mounted upon the shuttle ring of said machine operatively connecting the shuttle with said oscillating cam during a portion of the tying cycle and connecting the shuttle with the fixed cam during the remaining portion of the tying cycle.

35. In a tying machine a reversely revolable shuttle ring, an oscillatory shuttle means suitably secured thereto, means to turn the ring to encircle a package with wire and to restore the wire to its initial position, means to cut off a length of wire, and means to twist the wire into a splice between its ends.

36. In a tying machine a supporting frame, suitable operating mechanism mounted therein, a shuttle ring rotatably mounted upon said frame, means associated with said operating mechanism for reversely rotating said ring, a shuttle pivotally mounted upon said ring, means associated with said operating mechanism for oscillating said shuttle, a plurality of grippers associated with said frame, means associated with said operative mechanism for independently operating each of said grippers, cutting means with said operative mechanism for independently operating each of said grippers, cutting means associated with said grippers, twister means, means associated with said operating mechanism for actuating said twister.

37. In a tying machine a supporting frame, suitable operating mechanism mounted therein, a shuttle ring rotatably mounted upon said frame, means associated with said operating

mechanism for reversely rotating said ring, a shuttle pivotally mounted upon said ring, means associated with said operating mechanism for oscillating said shuttle, a plurality of grippers associated with said frame, means associated with said operative mechanism for independently operating each of said grippers, cutting means associated with said grippers, twister means, means associated with said operating mechanism for actuating said twister, ejector means mounted upon said frame, means associated with said operating mechanism for actuating said ejector means.

38. In a tying machine a supporting frame, suitable operating mechanism mounted therein, a shuttle ring rotatably mounted upon said frame, means associated with said operating mechanism for reversely rotating said ring, a shuttle pivotally mounted upon said ring, means associated with said operating mechanism for oscillating said shuttle, a plurality of grippers associated with said frame, means associated with said operative mechanism for independently operating each of said grippers, cutting means associated with said grippers, twister means, means associated with said operating mechanism for actuating said twister, ejector means mounted upon said frame, means associated with said operating mechanism for actuating said ejector means, a package holding means associated with said frame, means associated with said operating mechanism for operating said holding means.

39. In a tying machine a supporting frame, suitable operating mechanism mounted therein, a shuttle ring rotatably mounted upon said frame, means associated with said operating mechanism for reversely rotating said ring, a shuttle pivotally mounted upon said ring, means associated with said operating mechanism for oscillating said shuttle, a plurality of grippers associated with said frame, means associated with said operative mechanism for independently operating each of said grippers, cutting means associated with said grippers, twister means, means associated with said operating mechanism for actuating said twister, ejector means mounted upon said frame, means associated with said operating mechanism for actuating said ejector means, a package holding means associated with said frame, means associated with said operating mechanism for operating said holding means.

40. In a package tying machine, a supporting frame, a reversely revolvable shuttle ring rotatably mounted thereon, a shuttle having a uni-directional wire feeding means secured to said shuttle ring, means to supply said shuttle with wire under a predetermined tension, means to support a package adjacent said ring, a pair of spaced grippers in line with the wire, independent operating means for each of said grippers, a means positioned between said grippers for twisting the wire into a flat splice along one side of the package.

GUY A. DUNN.
JOHN ELDRIDGE.
